UNITED STATES PATENT OFFICE.

SAMUEL L. CONDE, OF ROCKFORD, ILLINOIS.

DESIGN FOR A TYPE-WRITER CABINET.

SPECIFICATION forming part of Design No. 22,398, dated May 2, 1893.

Application filed February 24, 1893. Serial No. 463,645. Term of patent 7 years.

To all whom it may concern:

Be it known that I, SAMUEL L. CONDE, a citizen of the United States, residing at Rockford, in the county of Winnebago and State 5 of Illinois, have invented and produced a new and original Design for Type-Writing Cabinets, of which the following is a specification, reference being had to the accompanying drawing, in which the design is represented in perspective.

The cabinet is composed of ends 1 having their rear edges straight and their front edges curved inward at the top as shown at a and cut away at their lower portions as shown at 15 b. To the top of the side pieces is secured a shelf 3 having a back 4 and end pieces c provided with rounded corners. d denotes posts having rounded heads. The sides 1 have two parallel straight grooves connected at their ends by the curved grooves g. 20 10 denotes the sliding curtain and 5 the drawers.

The leading feature of the design are the sides having straight rear edges, the front edges cut away at b and curved at a, the 25 grooves e, f and g, the shelf, having a back 4 and ends c the corners of which are rounded and the rounded posts d.

What I claim is—

A design for a type writer cabinet herein 30 shown and described.
